(57) **CLAIM**

The ornamental design for a fishing rod handle, as shown and described.

DESCRIPTION

FIG. 1 is a perspective view of a fishing rod handle showing my new design;

FIG. 2 is a right side view thereof;

FIG. 3 is a left side view thereof; the left side being a mirror image of the right side;

FIG. 4 is a top view thereof;

FIG. 5 is a bottom view thereof;

FIG. 6 is a rear view thereof;

FIG. 7 is a front view thereof; and,

FIG. 8 is a right side view thereof with a reel and rod attached thereto for illustrative purposes only. The subject matter shown in broken lines, including the reel and rod, do not constitute any part of the claimed designs.
